(57) **CLAIM**

The ornamental design for an analog gauge needle, as shown and described.

DESCRIPTION

FIG. 1 is a first perspective view of a first embodiment of an analog gauge needle.

FIG. 2 is a second perspective view thereof.

FIG. 3 is a top view thereof.

FIG. 4 is a bottom view thereof.

FIG. 5 is a first end view thereof.

FIG. 6 is an opposite second end view thereof.

FIG. 7 is a first side view thereof.

FIG. 8 is an opposite second side view thereof.

FIG. 9 is a first perspective view of a second embodiment of an analog gauge needle.

FIG. 10 is a second perspective view thereof.

FIG. 11 is a top view thereof.

FIG. 12 is a bottom view thereof.

FIG. 13 is a first end view thereof.

FIG. 14 is an opposite second end view thereof.

FIG. 15 is a first side view thereof; and,

FIG. 16 is an opposite second side view thereof.

The broken lines represent portions of an analog gauge needle that form no part of the claimed design.
